UNITED STATES PATENT OFFICE

2,554,587

SHEET MATERIAL GLUING MACHINE

Robert Minkow, New York, N. Y.

Application January 14, 1948, Serial No. 2,270

3 Claims. (Cl. 91—51)

1

This invention relates to gluing machines for applying glue to sheet material, and is an improvement over the machine embodied in my copending application, Serial No. 594,895, filed May 21, 1945, for Gluing Machine, and now Patent No. 2,461,388.

An object of this invention is to provide a gluing machine for applying a film of glue to sheet material wherein the pressure or feeding rolls are connected to the table and are mounted so that they may be lifted up to expose the glue reservoir, so that the latter may be filled, cleaned or the like.

Another object of this invention is to provide a machine of this kind including an improved mounting for the gluing roller and the film regulating roller so that these rollers can be removed and inserted without the use of tools.

A further object of this invention is to provide a spring-pressed pressure roller disposed in advance of the feeding roller or rollers with manually operable release means for moving said pressure or guide roller to released position.

A further object of this invention is to provide a gluing machine which can be used with flexible sheet material such as paper, leatherette or the like, or may be used with relatively stiff material, such as cardboard, corrugated board, wood or the like.

A further object of this invention is to provide in a machine of this kind self-lubricating bearings for one or more of the rollers so that the lubricant will not mix with the glue.

A further object of this invention is to provide a machine of this kind which includes a thermostatic heat regulating means in the glue reservoir which is disposed beneath the gluing roller so as to maintain the glue at the desired temperature within the gluing zone.

In the drawings:

Figure 1 is a detailed side elevation of a gluing machine constructed according to an embodiment of this invention.

Figure 2 is a plan view of the machine.

Figure 3 is a plan view of the machine with the table and feeding rolls removed.

Figure 4 is a fragmentary sectional view taken on the line 4—4 of Figure 2.

Figure 5 is a sectional view taken on the line 5—5 of Figures 1 and 2.

Figure 6 is a fragmentary sectional view taken on the line 6—6 of Figure 2.

Figure 7 is a fragmentary sectional view taken on the line 7—7 of Figure 1.

Figure 8 is a detailed side elevation of the ma-

2

chine opposite from that shown in Figure 1 and showing the table and guard in dotted and up-raised position.

Figure 9 is a fragmentary sectional view taken on the line 9—9 of Figure 2.

Figure 10 is a fragmentary sectional view taken on the line 10—10 of Figure 1.

Figure 11 is a fragmentary sectional view taken on the line 11—11 of Figure 6.

Figure 12 is a fragmentary bottom plan of the pointer carried by the table.

Figure 13 is a fragmentary sectional view taken on the line 13—13 of Figure 2.

Figure 14 is a fragmentary sectional view taken on the line 14—14 of Figure 8.

Figure 15 is a fragmentary sectional view taken substantially on the line 15—15 of Figure 5.

Figure 16 is a fragmentary sectional view of one of the self-lubricating bearings for the gluing roller.

Figure 17 is an end elevation of one of the self-lubricating bearings.

Figure 18 is a fragmentary detailed side elevation of the rear portion of the machine with the feeding rollers and table in raised inoperative position.

Figure 19 is a fragmentary longitudinal section of a modified form of this invention.

Figure 20 is a fragmentary vertical section of another modification of this invention.

Figure 21 is a fragmentary sectional view taken on the line 21—21 of Figure 20.

Figure 22 is a fragmentary sectional view taken on the line 22—22 of Figure 6.

Figure 23 is a fragmentary sectional view taken on the line 23—23 of Figure 6.

Referring to the drawings, the numeral 25 designates generally a base structure which is formed of opposite side members 26 and 27, opposite end members 28 and 29 and a bottom 30 which is fixed between the side and end members so as to thereby form a glue reservoir or well 31. The bottom member 30 is formed with a downwardly offset bottom member 32 which forms a depressed well 33 and the well 33 communicates through an opening 34, as shown in Figure 15, with a valve housing 35 which is fixed by fastening members 36 to the side wall 27. The housing 35 has pivotally secured to the lower side thereof a flat valve plate 37 which is mounted on a pivot bolt 38 and a spring-pressed bolt 39 extends through an arcuate slot 40 formed in the valve plate 37. In this manner the valve plate 37 is constantly urged upwardly

to sealing position against the lower side of the valve housing 35.

A handle 41 is secured to and extends rearwardly from the valve plate 37 and is adapted to be swung outwardly or forwardly to provide for the draining of the glue in the auxiliary or lower well 33. The side members 26 and 27 have fixed to the forward end portions thereof elongated horizontally disposed bars 42 and 43, respectively, and the bars 42 and 43 are each formed with upwardly opening slots 44 and 45, respectively, within which self-lubricating bearings 46 are adapted to removably engage. The bearings 46 are frictionally disposed in the slots 44 and 45 and each bearing 46, as shown in Figures 16 and 17, includes a cylindrical member 47 which is formed with a plurality of radially disposed openings 48 within which substantially solid lubricating plugs 49 are adapted to be mounted.

A gluing roller 50 is rotatably carried by the bearings 46, the roller 50 includes outwardly extending trunnions 51 and 52 which are journaled in the bearings 46 and trunnion 51 has fixed to the outer end thereof a feed roller operating gear 53. The trunnion 52 has fixed thereto a relatively large spur gear 54 which meshes with a relatively small gear 55 which is carried by a pulley shaft 56 on which a pulley 57 is fixedly secured. The pulley 57 also has extending endwise and outwardly therefrom a cylindrical pulley operator 58 by means of which the pulley 57 may be manually rotated when it is desired to effect manual rotation in either direction of the gluing roller 50 and the feeding rollers to be hereinafter described.

The pulley 57 has engaging thereabout an endless belt 59 which also engages about a driving pulley 60 mounted on a motor shaft 61. A motor 62 is disposed in an inwardly offset rear portion 63 which is formed in the side wall 26 so that the motor 62 will be substantially contained by the opposite sides of the base. A pair of side arms 64 are disposed at the forward portion of the base and are pivotally mounted on pivot members 65 carried by plates 66 which are secured to the forward inner portions of the bars 42 and 43. The side bars 46 are of elongated configuration and have secured to the lower sides thereof a flat table 67. The table 67 is adapted to be adjusted in substantially horizontal position by means of one or more pairs of table supporting bolts 68 which are threaded into the upper edges of the sides of the base 25. The table 67 is formed at its rear end with a downwardly curved apron 69, as shown in Figure 8, and this apron engages over the downwardly curved rear end portion of a guard 70 which is fixed by fastening members 71 to one lengthwise edge of the table 67.

The guard 70 includes a horizontally disposed and outwardly extending upper portion 72 and a vertical side 73. The guard 70 also includes a rear arcuate guard member 74 which is hingedly secured to the main body of the guard by hinge means 75. The rear arcuate guard 74 engages partly about the pulley 57 and is formed with a relatively large opening 76 correlating with a similar opening 77 through which the hand wheel 58 is adapted to project. The hinged or rear arcuate guard member 74 is held in operative position by means of a bolt 78 which is threaded into the adjacent side wall 26 and has a sleeve or spacer 79 engaging thereabout. If the main body of the guard 70 is raised with the upward swinging of the table and the side arms

or bars 64, the arcuate rear guard members 74 will move downwardly and rearwardly as shown in dotted lines in Figure 8. The side bars or arms 64 include upwardly projecting bearing guides 80 which are formed with a pair of openings 81 within which bearing members 82 are slidably mounted.

A pair of feeding and pressure rollers 83 mounted on shafts 84 are rotatably carried by the bearing members 82 and are spring-pressed downwardly by means of springs 85 which engage about an adjusting bolt 86. The bolt 86 extends upwardly through a bushing 87 carried by a base block 88 which is secured to the upper side of the guide member 80. A bearing adjusting nut 89 is threaded on the bolt 86 bearing at its lower end against the bushing 87 and a lock nut 90 is threaded on the upper end of the bolt 86 and is adapted to lock the bolt 86 in adjusted position.

The shafts 84 for the feed rollers 83 have secured to one end thereof spur gears 91 which mesh with an intermediate gear 92 rotatably mounted on a stud 93 which is fixed to the guide 80. The intermediate gear 92 meshes with a second gear 94 and the latter meshes with the glue roller gear 53.

The bearing bars 43 at a point rearwardly from the slots 44 and 45 are formed with upwardly opening slots 95 within which blocks 96 are slidably mounted. The blocks for the doctor roller 97 which extends across the base 25 and the trunnions 98 at the ends of the doctor roller 97 rotatably engage in bearing bushings 99 mounted in the bearing blocks 96. Each bearing block 96, as shown in Figures 6 and 22, includes an inner flange 100 slidably engaging against the inner side of the adjacent bar 43. In order to provide for quick removal of the bearing blocks 96 for removing the doctor roller, the bars 43 have secured thereto an inwardly projecting locking member 101 which engages over the upper edge of the inner end of the flange 100. Each bearing block 96 has secured thereto a rearwardly extending threaded bolt 102 on which an adjusting wheel 103 is threadably mounted.

The bar 43 is formed with a cut-out 104 within which a bearing tensioning spring 105 engaging about the bolt 102 is adapted to be disposed. The rear end of the spring 105 bears against a washer 106 which is interposed between the spring 105 and the rear end of the cut-out 104. The bar 43 is formed with an upwardly opening slot 107 through which the bolt 102 engages and an operator sleeve 108 is engaged in the slot 107 being interposed between the washer 106 and the forward end of the adjusting wheel 103.

The adjusting wheel 103 engages in an inwardly offset side wall portion 109 formed in the side wall 27 and a similar offset portion 110 formed in the side wall 26. There are two of these wheels 103 as shown in Figures 2 and 3. The doctor roller 97 has secured to one trunnion 98 thereof a spur gear 111 which meshes with a spur gear 112 which is fixed to trunnion 52 of the gluing roller 50.

A guide roller 113 is rotatably carried by a pair of bearing blocks 114 which engage in guide slots 115 formed in the bars 64. The bearing blocks 114 are adjusted in the slots or openings 115 by means of a threaded adjusting bolt 116 which extends through a bushing 117 having a base flange 118 which is secured by fastening members 119 to the bar 64 at the rear side of

75 the guide member 80.

A spring 120 is disposed in the bushing 117 and bears at its lower or forward end against the bearing block 114 and at its upper end against a shoulder 121 formed in the upper rear end of the bushing 117. An adjusting nut 122 is threaded on the bolt 116 and is locked in adjusted position by a lock nut 123. The slot 115 is disposed on an angle to the vertical and preferably on a radius of the gluing roller 50. The guide roller 113 is adapted to be swung upwardly and rearwardly to released position by means of a pair of releasing lugs or levers 124 which bear against the roller 113 adjacent the opposite ends thereof. The lug or lever 124 includes a bushing 125 which is rotatable on an adjacent pressure roller stud such as 81 and the bushing 125 has extending upwardly and forwardly therefrom an arm 126. There are two of these adjusting arms 126 which are connected together by a connecting bar 127. In order to hold the guide bar 113 in released position, I have provided a pair of hooks 128 which are loosely disposed about the foremost shaft or trunnion 84 for the feed rollers and the hook 128 includes a bill 129 adapted to engage over the connecting bar 127. When in released position the hook 128 will be dependably disposed at the opposite ends of the foremost feeding roller 83. When the sheet is passed between the gluing roller 50 and the feeding rollers 83 the sheet is stripped from the gluing roller by means of a plurality of stripping fingers 130 which are carried by arms 131 loosely disposed on a transversely extending supporting rod 132. The opposite ends of the supporting rod 132 are engaged in a selected notch 133 formed in the plate 65.

The stripping fingers 130 are adapted to gravitantly engage the periphery of the roller 50 so as to strip the sheet from the roller and permit this sheet to pass forwardly.

The gluing well or chamber 31 has mounted therein a thermostat 134 which is disposed below the gluing roller 50, as shown in Figure 4, and in substantially the vertical plane of the meeting point between the two rollers 50 and 97. The base 25 includes a heating chamber 135 below the bottom wall 30 and an insulated plate 136 is secured to the base 25 below the heating element (not shown) which is of conventional construction.

The heating element within the chamber 135 is connected to a rheostat 137 and a switch 138 is also connected to the rheostat 137 and the heating element. A switch 139 is disposed adjacent the switch 138 and is connected to the motor 62. A signal or pilot light 140 is disposed adjacent the rheostat 137 and a fuse 141 is connected in the electric circuit associated with the rheostat 137. The rheostat 137, the two switches 138 and 139, the signal light 140 and the fuse 141 are carried by a housing 142 which is fixed to the outer side of the side wall 27.

As shown in Figure 9, the arms 126 for the releasing means for the guide roller 113 are limited in their forward swinging to released position by stop pins 143 which are secured to the guide members 80 and project inwardly therefrom.

Referring now to Figure 19, there is disclosed a modified form of this invention which includes a gluing roller 50a. A single feeding roller 83a is disposed above the gluing roller 50a being rotatably carried by spring tensioned bearing blocks 82a.

Referring now to Figure 20, there is disclosed a

modified form of guide roller release wherein a releasing lever, generally designated as 144, is rockably mounted on the associated feed roller shaft 84a. The releasing lever 144 includes an arm 145 which is adapted to engage the adjacent bearing block 114a for the guide roller 113a. There are two of these releasing levers 144 which are connected together by means of a connecting bar 146 and, if desired, the holding hooks such as the hooks 128 may be used to hold the releasing levers 144 in released position.

When the table 67 is raised upwardly and the bars 64 raised therewith carrying the feed rollers 83 the guide members 80 are adapted to engage upwardly projecting stop bolts 147 which are secured to the forward portion of the base 25.

In the use and operation of this machine the sheet material which is to be coated with glue on at least one side thereof is moved flatwise over the upper surface of the table 67. The guide rollers 113 which may also constitute pressure rollers are adjusted and tensioned to the desired degree so that the lower side of the sheet will contact with the rotating gluing roller 50. The doctor roller 97 is adjusted and tensioned by rotating the adjusting wheels 103 and these wheels include numerals or graduations 148 which are correlated with a pointer 149 secured by fastening members 150 to the lower side of the table 67. As the glued sheet passes beneath the feeding rollers 83 these rollers will move the sheet forwardly and the stripping fingers 130 will strip the now glued sheet from the roller 50. When it is desired to fill the gluing well or reservoir 31 with glue, the table 67 is raised and the glue poured into the well 31 from the top. In the event it is desired to remove the doctor roller 97, this can be accomplished by rotating the wheels 103 to release the tension on the springs 105 whereupon with the table 67 in raised position the hand wheels 103 may be pulled upwardly thereby turning the bearing blocks 96 and releasing these bearing blocks from the locking bars 101. The gluing roller 50 may be readily removed by merely raising the table 67 and pulling the roller bodily upwardly with the self-lubricating bearings 47.

I claim:

1. In a gluing machine, a base, a gluing roller rotatably carried by said base, a doctor roller correlated with said gluing roller, said base including a pair of horizontally disposed upwardly opening bearing guides, bearings for said doctor roller slidably engaging within said guides, an upwardly opening slot formed in said base in alignment with each of said bearing guides, bearing tensioning means disposed in each of said slots and engaging said bearings and said base, a pair of elongated feed and pressure roller supports pivoted above said base and formed with flat lower edges adapted in the horizontal position thereof to overlie said bearing guides to prevent removal of said bearings therefrom whereby when said supports are pivoted upwardly said doctor roller, said bearings, and said tensioning means may be removed as a unit upwardly from said base.

2. In a gluing machine, a base, a gluing roller rotatably carried by said base, a doctor roller correlated with said gluing roller, said base including a pair of horizontally disposed upwardly opening bearing guides, bearings for said doctor roller slidably engaging within said guides for horizontal movement towards and away from said gluing roller, bearing tensioning means including

a horizontally disposed bolt fixed to each of said bearings, upstanding portions on said base formed with an upwardly opening slot adapted to loosely receive said bolt, spring means disposed between each of said bearings and said upstanding portions for constantly urging said doctor roller towards said gluing roller, an adjusting member threadedly engaging each of said bolts and bearings against said upstanding portions for adjusting the tension of said spring means, a pair of elongated feed and pressure roller supports disposed above said base and pivotally connected thereto, said supports having flat lower edges adapted, when horizontally disposed, to overlie said bearing guides to prevent removal of said bearings therefrom whereby when said supports are pivoted upwardly said doctor roller, said bearings and said bearing tensioning means may be removed upwardly as a unit from said base.

3. In a gluing machine, a base including a pair of upstanding side walls, a gluing roller having the opposite ends thereof rotatably carried by said side walls, a doctor roller correlated with said gluing roller, a horizontally disposed upwardly opening bearing guide formed in each of said side walls, a bearing block rotatably carried by each of the opposite ends of said doctor roller and adapted to slidably engage within the adjacent bearing guide, a flange formed on the inner surface of each of said bearing blocks and adapted to slidably engage the inner surface of the adjacent side wall, an inwardly directed member fixed to the top of each of said side walls

5 at one end of said bearing guides and adapted to overlie said flange to prevent upward movement of said bearings, bearing tensioning means disposed between said bearing blocks and said side walls and adapted to constantly urge said doctor roller towards said gluing roller, a pair of elongated feed and pressure roller supports disposed above said side walls and pivoted thereto and having flat lower edges adapted in the horizontal position thereof, to overlie said bearing guides to prevent upward movement of said bearing blocks whereby when said supports are pivoted upwardly said bearing blocks and said tensioning means may be rocked upwardly and away from said inwardly directed members to permit removal of said doctor roller, said bearing blocks, and said tensioning means from said base as a unit.

ROBERT MINKOW.
